UNITED STATES PATENT OFFICE.

ANSON J. BENTLEY, OF NILES, OHIO.

FREEZING CAN.

Application filed August 4, 1922. Serial No. 579,568.

To all whom it may concern:

Be it known that I, ANSON J. BENTLEY, a citizen of the United States, and a resident of the city of Niles, county of Trumbull, and State of Ohio, have invented an Improvement in Freezing Cans, of which the following is a specification.

The present invention relates to improvements in freezing cans used in the manufacture of ice and particularly to an improved construction of can wherein means are provided to force air into the can at or near the bottom to agitate the water which is to be frozen; this being the commonly accepted practice in what is known as the raw water can system of ice making.

In this system it is customary to use freezing cans immersed in an appropriate freezing solution, such as brine, which is circulated around the cans. In order that the impurities commonly present in water available for the manufacture of ice may not be frozen into the finished cakes, some means are provided for introducing air into the can at or near the bottom. The action of this air current upon the water is such that the impurities are not frozen into the ice, but are collected in the small amount of water which remains unfrozen in a pocket in the ice cake at the termination of the freezing period.

In order to introduce this air it has been customary heretofore to provide some sort of a tube or pipe running from the top edge of the can downward to a point at or near the bottom and there opening into the interior of the can. Cans of this type can be economically manufactured to provide an air conduit in the wall of the can by shaping the wall member itself to form the conduit. See, for example, my co-pending application Serial No. 433,163, filed December 27, 1920. In cans of this type as compared with cans having inserted tubes difficulty is involved in making an air conduit connection between an air nozzle and the top of the conduit. It is impracticable to shape the walls of the conduit to form a tight connection with the air nozzle since the galvanized surfaces of the sheet metal used in cans is not sufficiently smooth and regular and if the galvanized surface is removed to form the joint the material rusts under the effect of the water and brine with which these cans are used.

It is an object of the present invention to

provide a construction of the freezing can in which a conduit for the introduction of air in accordance with the raw water system may be formed of sheet metal and yet may economically and effectively be arranged for convenient attachment of an air hose.

The nature and objects of the invention will be better understood from a description of an illustrative embodiment thereof, reference being had to the accompanying drawings forming a part hereof in which

Figure 1 is a perspective view of a freezing can embodying the invention.

Figure 2 is a perspective view on a larger scale of a portion of the interior of the can indicating the manner in which the connector is applied to the can.

Figure 3 is a top plan view of the same.

Figure 4 is a view showing a portion of the blank from which the can is made indicating the provision of extra metal for forming the enlarged upper end of the air conduit.

Figure 5 is a sectional view taken on the line 5—5 of Figures 3 and 6.

Figure 6 is a sectional view taken on the line 6—6 of Figure 3.

Figure 7 is a view of the hose connector adapted to be used with the can illustrated.

The general construction of the freezing can shown herein may be for example such as illustrated in my co-pending application Serial No. 433,163, filed December 27, 1920, in which an air conduit extending down the side of the can is provided by deforming a side member of the can at or near a vertical seam.

In the particular structure selected for the purposes of illustration the conduit 5 is formed at a vertical seam between overlapping wall portions 6, 7 by deforming the inner portion between the two rows of rivets 8, 9. To provide the desired connection for an air supply there is provided at the upper end of the conduit a connector 10 adapted to form a substantially air-tight connection with a hose connector. The connector is substantially flush with or depressed below the top of the freezing can for the reason that projecting parts which could be easily damaged are seriously objectionable on account of the rough handling to which these cans are subjected in use. The connector may be formed in any suitable way for attachment of an appropriate hose connector. In the arrangement

shown it is a bushing with a flat side 11 having a bore 14 formed to receive therein the simple tubular and preferably tapered hose connector 15 best shown in Figure 7.

5 The connection between the conduit and the connector may be made in any suitable way but preferably the connector is inserted for at least a part of its length in the upper end of the conduit. In the illustrated structure the full length of the bushing 10 is inserted in the conduit 5 and it is soldered securely therein to form an air-tight connection. The conduit may be made relatively small throughout the greater portion 15 of its length and only the upper portion enlarged sufficiently to receive the bushing. Such a structure is illustrated in the drawing. As herein shown the larger section is formed at the top of the can by providing a 20 greater width of stock in the blank as indicated at 16 in Figure 4. When the blank is bent to form the conduit this additional stock permits forming the enlarged portion without stretching the stock and therefore, 25 if the can is constructed of galvanized metal, without destroying the galvanized surface.

The structure shown is to be understood as illustrative merely since variations may be made in the structure without departing 30 from the spirit of the invention as set forth in the claims.

I claim as my invention:

1. A freezing can for use in the manufacture of ice having a conduit formed by 35 a distortion of the wall material extending downwardly along one wall, the upper end of the conduit being enlarged and having secured therein a bushing presenting a bore substantially equal to the bore of the conduit 40 throughout its length.

2. A freezing can for use in the manufacture of ice having a downwardly extending conduit formed between parts secured together by two rows of rivets and spaced 45 apart therebetween and having secured in the upper end of the conduit and even with the top thereof a bushing having a bore to fit an air nozzle, said bushing lying within the conduit throughout substantially its 50 whole length.

3. A freezing can for use in the manufacture of ice, one wall of which comprises a plurality of thicknesses of material se-

cured together by spaced rows of rivets, one thickness being formed to provide between 55 itself and the next thickness a vertical air passage, said air passage being enlarged at its upper end and a bushing secured in the enlarged portion and having a bore to receive an air hose connector. 60

4. A freezing can for use in the manufacture of ice, comprising wall members and a bottom member, and having one of the wall members grooved inwardly where it overlaps the other wall member and united thereto on each side of the groove thereby forming an integral air conduit, said groove being enlarged at its upper end and having a bushing inserted therein, the bore of the bushing being arranged to receive an air 70 hose connector therein.

5. A freezing can for use in the manufacture of ice having wall members arranged to provide an air conduit, the conduit being enlarged at its upper end, and a tubular connector secured in the enlarged portion 75 and formed for the attachment of an air hose connector.

6. A freezing can for use in the manufacture of ice having wall members arranged 80 to provide an air conduit, the conduit being enlarged at its upper end and a tubular connector secured in the enlarged portion substantially even at the top with the end of the conduit and having a bore for the attachment of an air hose connector. 85

7. In an ice can, sheet metal forming the walls of the can, the ends of said sheet metal overlapping and lying in superimposed relationship, one of said overlapping ends being bent to provide a portion offset from the other end and cooperating with the other end to form a vertical air passage in the walls of the can between said overlapping ends, said offset portion being formed to provide an enlargement of the passage at the top of the can and having an opening therein in its lower end providing communication between the air passage and the inside of the can and a bushing in the enlargement having a tapered bore to receive an air hose connector. 90 95 100

In testimony whereof, I have signed my name to this specification this 29 day of July, 1922.

ANSON J. BENTLEY.
